UNITED STATES PATENT OFFICE.

WILLIAM J. McWILLIAMS, OF LOST CABIN, WYOMING.

WAGON-TONGUE HOUNDS.

1,079,873.

Specification of Letters Patent. Patented Nov. 25, 1913.

Application filed May 13, 1913. Serial No. 767,325.

To all whom it may concern:

Be it known that I, WILLIAM J. McWILLIAMS, a citizen of the United States, residing at Lost Cabin, in the county of Fremont and State of Wyoming, have invented certain new and useful Improvements in Wagon-Tongue Hounds, of which the following is a specification.

This invention relates to improvements in 10 wagons and more particularly to the construction of the fore hounds thereof.

The object in view is the provision of means enabling the application of tongues of various sizes to wagons of different 15 makes.

With this and further objects in view, as will in part hereinafter become apparent and in part be stated, the invention comprises tongue hounds adapted to be fitted between the fore hounds of a wagon, cross 20 braces adjustably connecting the tongue hounds, and adjustable links also connecting the hounds for spacing the same at variable distances, the said cross braces and links being adapted to be connected to a tongue.

The invention also comprises certain other novel constructions, combinations and arrangement of parts as will be hereinafter specified and claimed.

30 In the accompanying drawing:—Figure 1 is a top plan view of a fragment of a wagon structure illustrating the embodiment of the invention, parts being seen in horizontal section. Fig. 2 is a transverse, vertical section taken on the plane indicated by line 2—2 of Fig. 1, the wagon hounds being omitted. Fig. 3 is an enlarged, detail, fragmentary section taken approximately on the plane indicated by line 3—3 of Fig. 1. Fig. 4 is 40 a horizontal section taken on the plane indicated by the line 4—4 of Fig. 3, parts being seen in elevation.

Referring to the drawing by numerals, 1, 1 indicate the fore hounds of a wagon fitted 45 to which are the tongue hounds 2, 2, each of the latter being preferably in the form of a channel beam or bar having a vertical web fitted flat against the adjacent vertical face of the respective hound 1. A tongue 3 is disposed between the hounds 2 and connected thereto by cross braces 4, 4 and by links 5, 5. Each of the cross braces 4 has its outer end terminating in an eye 6 disposed between the horizontal flanges of the 50 respective hound 2 and connected thereto by a pivot bolt 7. The inner end portions of

the braces 4 extend through an aperture in the tongue 3 and lap therein and extend preferably to the relatively opposite sides of the tongue through the aperture. A preferably metallic sleeve 8 surrounds the tongue 3 at the place of the aperture for accommodating the cross braces 4, the sleeve 8 being formed with lateral apertures registering with the aperture of the tongue and also accommodating the cross braces 4 which extend through the apertures of the sleeve. A bolt or set screw 9 is threaded through the sleeve 8 and through the material of the upper portion of the tongue into engagement 60 with the uppermost cross brace 4. The contiguous faces of the braces 4 are preferably serrated, as indicated at 10, and the bolt 9 is adapted to press the cross braces together for maintaining the interlocked condition of 65 the serrations whereby the cross braces 4 are held rigidly connected and at the same time rigidly adjustable longitudinally for varying the relative distance apart of the hounds 2, and their relative inclination with respect to the longitudinal axis of the tongue. 70 Adjacent the forward ends of the hounds 2 each of the same is engaged by a pair of the links 5, the outer ends of said links being pivoted to the respective hound by a bolt 11 75 extending through thelapping ends of the links and through the horizontal flanges of the hound, and the inner end of each rear link 5 is pivotally connected by a pivot bolt 12 to a bracket 13, each forward link 5 being likewise pivotally connected by a bolt 14 80 to a forward bracket 15. The brackets 13 are connected to the tongue 3 by through bolts 16, and the brackets 15 are connected to the tongue 3 by similar through bolts 17. 85

A main bolt 18 which connects the tongue with the wagon extends through the outer end portions of the hounds 1 and through appropriate apertures in the vertical webs of the hounds 2 and through the tongue 3 in 90 advance of the sleeve 8.

It is, of course, a well known fact that there are slight variations in the sizes of the wagon hounds of the various makes of wagons, and it is therefore usually impracticable to apply a tongue of one make to a wagon of another, so that the user of a wagon is ordinarily compelled to purchase from the regular manufacturer whenever he finds his wagon in need of a new tongue. 100 This sometimes proves undesirable or impracticable for various reasons, and to avoid 105

the necessity therefor, the present invention provides for the adaptation of the tongue hounds to fit the hounds of any of the standard makes of wagons. When the tongue 3 becomes broken, to renew the same only requires the removal of the remaining piece of the tongue by removing the bolts 17 and 16 and disconnecting the bolt 9, sleeve 8 and cross braces 4, and replacing the new tongue 10 in place of the old, the new tongue in the meantime having been drilled with apertures for accommodating the cross braces 4, and the bolts 9, 16 and 17. Obviously, if the new tongue is not of the same size as the one formerly used the proper adjustment may be readily made by the longitudinal adjustment of the cross braces 4 and the pivotal adjustment of the links 5, the pivotal adjustment being attained by a positioning 20 of the brackets 13 and 15 either nearer together or farther apart, according to the inclination and spacing required for the hounds 2. The holes for the bolts 16 and 17 will, of course, be bored after having been 25 located subsequently to an appropriate adjustment of the parts.

The invention, of course, is also especially useful when it is desired to apply a tongue from one wagon to another, and this may be 30 accomplished merely by an appropriate ad-

justment of the hounds 2, the hounds being, of course, removed with the tongue by the withdrawal of the bolt 18.

Having thus described the invention, what is claimed as new is:—

In a device of the class described, the combination, with a tongue, of spaced tongue hounds adapted to engage wagon hounds, tongue engaging cross braces pivotally engaging the tongue hounds and extending through the tongue, the tongue being formed with an aperture for receiving the cross braces, a tongue engaging sleeve surrounding the cross braces and tongue, a set screw threaded through the sleeve and a portion 40 of the tongue and engaging one of the cross braces in a direction pressing one cross brace toward the other for clamping the cross braces together, a pair of links pivotally connected to each of the tongue hounds and 45 spaced from the cross braces, and means pivotally connecting the relatively opposite ends of said links to the tongue.

In testimony whereof I affix my signature in presence of two witnesses.

WILLIAM J. McWILLIAMS.
